UNITED STATES PATENT OFFICE.

STEPHEN J. CIRBUS, OF BUFFALO, NEW YORK.

ENVELOP SEALER AND STAMPER.

1,371,146.

Specification of Letters Patent.

Patented Mar. 8, 1921.

Application filed October 2, 1919. Serial No. 327,876.

To all whom it may concern:

Be it known that I, STEPHEN J. CIRBUS, a citizen of the United States, residing at Buffalo, in the county of Erie and State 5 of New York, have invented certain new and useful Improvements in Envelop Sealers and Stampers, of which the following is a specification.

This invention relates to improvements in 10 machines for preparing addressed envelopes for mailing and comprehends a machine wherein the envelopes are placed in a receiver and upon operation of the machine, carried forwardly out of the receiver under 15 a moistening element whereby the adhesive material upon the envelop flap is moistened and subsequently passed beneath a deflector which acts to fold the body of the envelop against the flap and means for finally compressing the envelop body and flap to securely seal the envelop.

Another object is the provision of a machine of this character wherein a stamp applying mechanism is interposed between 25 the flap moistening and compressing means and which is automatically actuated by the conveyer carrying the letter to apply a postage stamp thereto.

Another object is the provision of stamping mechanism for a machine of this character wherein the stamps are automatically fed from a supply roller between a pair of cutting rollers which are also automatically actuated to cut the stamp strip up into 35 predetermined lengths, one of the cutting rollers being equipped with moistening means whereby the stamp, prior to its application to the letter is moistened to cause its adhesion to the envelop.

With these and other objects in view as 40 will appear as the description proceeds the invention comprises the novel features of construction, combination of elements and arrangement of parts which will be more 45 fully described in the following specification and set forth with particularity in the claims appended hereto.

Figure 1 represents a side elevation of the improved sealing and stamping machine.

Fig. 2 represents a plan view thereof.

Fig. 3 represents an end elevation of the machine.

Fig. 4 represents an enlarged vertical sectional view taken longitudinally through 55 the machine illustrating the stamp applying mechanism in detail.

Fig. 5 represents a vertical transverse sectional view through the machine on the plane of the envelop flap moistener.

Referring to the drawing in detail, where- 60 in similar reference numerals designate corresponding parts throughout the several views, the numerals 5 indicate the opposed side members of a supporting frame structure which is open at both ends and also at 65 the top. Supporting rollers 6 and 7 are supported upon shafts adjacent the opposite ends of the frame structure and the shaft of the roller at the rear end of the frame structure is provided with a hand 70 crank 8 for convenience in manual manipulation of the machine. An endless conveyer belt or apron 9 is extended over and between the rollers 6 and 7 and is arranged in the plane of the relatively low portions 75 of the upper edges of the side members 5, the latter, at their rear extremities being increased in height as indicated at 10 to form the side walls of the envelop receiving chamber.

The receiving chamber for the envelopes is 80 designated by the numeral 11 in Fig. 2 and the portions of the side members 5 constituting the walls of the chamber are provided with transversely extending sup- 85 porting bars 12 which constitute guides and a support for a slide bar 13 which, as is illustrated in Fig. 3, is arranged in the upper portion of the chamber 11 and is provided with depending spring arms 14 90 designed to engage the innermost of a group of envelopes 15 confined between the spring fingers in one side of the frame structure. In placing the envelopes in the chamber 11 the latter are arranged edgewise and the 95 flaps 16 thereof are arranged one upon the other upon the belt or apron 9. The spring arms 14 are carried by a shaft 17 journaled in the depending terminal portions of the slide bar 13 and a counterbalancing weight 100 carried by an arm 18 of the shaft 17 normally maintains the spring arms in contact with the adjacent envelop of the stack 15.

A series of uniformly spaced lugs 19 are 105 arranged upon the outer surface of the conveyer belt or apron 9 at one edge thereof and are adapted to engage the outermost envelop of the series during operation of the machine and convey such envelop forwardly between the side members of the 110 frame structure 5. A stop bar 20 is arranged between the side members of the

frame structure at the forward portion of the receiving chamber 11 and is designed to prevent the entire group of envelops from being carried forward bodily with the 5 conveyer, sufficient space being left between one terminal of the stop bar and the side of the frame structure to permit one envelop to pass forwardly at a time with the belt due to engagement of the lug 19 with 10 said envelop. As one envelop is removed from the group the entire series is moved forwardly against the side of the frame structure by the action of the spring arms 14 which normally maintains one envelop in 15 position for engagement by the lugs of the conveyer.

A flap sealing element designated generally by the numeral 21 is arranged forwardly of the stop bar 20 and is provided 20 with an angular terminal communicating with a liquid reservoir 23 having a removable cap 24 permitting the reservoir to be filled with water or other liquid for moistening the adhesive material on the flaps on 25 the envelops. The terminal of the tube 22 opposite the reservoir 23 terminates in spaced relation to the adjacent side of the frame structure permitting the envelops to pass forwardly between the terminal of said 30 tubes and the frame structure and the underside of this terminal of the tube is formed with a slot receiving a strip of absorbent material 25 which extends below the bottom surface of the tube and is designed 35 to wipe across the inner surface of the envelop flap 16 as the latter passes forwardly thereunder. The tube 22 conducts the liquid from the reservoir 23 to the absorbent strip 25 and due to the absorbent 40 quality of the latter it is maintained in a saturated condition and effectively spreads a film of liquid over the inner surface of the envelop flap moistening the adhesive material thereon.

45 At the front end of the frame structure a presser roller 26 is arranged and is connected with the shaft of the front conveyer roller 7 by a train of gear wheels 27 which impart rotary motion to the presser roller 26 50 so as to positively feed the envelops from the discharge or forward end of the machine during operation. To insure an even distribution of pressure exerted by the roller 26 upon the envelop, said roller is preferably formed of felt or other yieldable material.

At a point intermediate the flap moistening element 21 and the presser roller 26, a stamp moistening and applying mechanism designated generally by the numeral 27^a is 60 arranged. The stamping mechanism comprises a stamp supporting roller 28 which is mounted for rotation with a shaft 29 journaled in bearings 30 provided upon the side members of the frame structure. Cutting rollers 29^a and 30^a are arranged forwardly

of the roller 28 and are supported for rotation with shafts 31 and 32 also journaled in the bearing members 30.

The shaft of the cutting roller 29^a is of hollow form and communicates at its outer 70 angular terminal with a reservoir 33 identical in connection to the reservoir 23 and designed to contain a supply of liquid which is conducted to the interior of the hollow roller 29^a by the tubular shaft 31. The 75 roller 29^a is formed with a series of relatively small perforations 34 and a lining of felt or other absorbent material 35 is arranged internally of the roller to prevent leakage of the liquid through the perforations thereof. The roller 29^a is formed with a transverse recess defining a cutting edge 36 which is adapted to coact with the projecting cutting edge 37 of the roller 30^a to sever the stamp strip into sections of the 80 proper length incident with the location of said rollers.

The stamp strip 38 is wound upon the roller 28 and the terminal of the strip is fed from under the roller 28 across the top 90 of the roller 29^a and between the latter and the roller 27^a, finally passing under the latter and having its adhesive portion disposed toward the upper surface of the conveyer belt 9.

A lever 39 is pivotally mounted upon the terminal of the shaft 29 and is provided in its upper extremity with a pivoted pawl 40 movable over the teeth of a ratchet wheel 41 rigidly secured to the shaft 29 whereby 100 movement of the lever 39 in one direction causes a corresponding rotary movement of the roller 28 due to the coöperation of the pawl 40 with the teeth of the ratchet wheel 41. The movement of the shaft 29 is transmitted to the shaft 31 through a train of 105 gears 42 and the relative size of the gear wheels 42 is such that a complete revolution of the shaft 31 is effected at each oscillation of the lever 39, the motion of the shaft 31 110 being transmitted to the shaft 32 by the gear wheel 42 of the shaft 31 which meshes with a similar gear wheel 43 on the shaft 32. The lower extremity of the lever 39 is pivotally connected with a push rod 44 having 115

an angular extremity 45 which extends through an inclined slot 46 in the wall of the frame structure 5 above the upper portion of the conveyer belt 9. The angular extremity 45 of the push rod is disposed in the path of the lugs 19 as the latter move forwardly with the conveyer belt and incident to contact of the lugs with the angular extremity of the rod the latter is pushed forwardly causing an oscillation of the lever 39, the latter being returned to its initial position subsequent to an operation thereof by the tension of a spring 47. The slot 46 in the side of the frame structure is inclined 125 upwardly from its rear extremity so that as 130

the angular extremity 45 of the push rod is moved forwardly with the lug 19 it is gradually elevated until it is removed from the path of the lug and permits the latter to move forwardly with the conveyer belt also permitting the lever to be returned to its initial position under the influence of the spring 47.

A guide rod 48 is arranged in the frame structure above the belt 9 and is disposed obliquely to the longitudinal axis of the frame structure whereby as the front edges of the envelops engage therewith during their forward movement they are caused to fall back upon the conveyer belt, face upward, as shown in Fig. 2 and thus as the envelops are fed forwardly with the conveyer belt the stamp is applied to the front face thereof.

20 In use, the envelops which have been addressed and are in condition for mailing are placed in the receiving chamber 11 edgewise as suggested in Fig. 2 with the flaps 16 thereof open and lying one upon the other 25 upon the belt 9. The liquid reservoirs 23 and 33 having been previously supplied with a quantity of water or other fluid, the hand crank 8 is operated to cause movement of the conveyer belt 9.

30 The hand crank is revolved in a direction to cause forward movement of the upper portion of the conveyer belt and as the lug 19 is engaged with the edge of the envelop obstructing its movement, said envelop is 35 moved forwardly, the inner side of the flap 16 entering beneath the absorbent strip 25 and having a film of water or other liquid applied thereto which moistens and softens the adhesive material on said flap insuring 40 adhesion of the latter to the body of the envelop when the latter is folded upon the flap. During the continued forward movement of the envelop the body thereof is engaged with the obliquely disposed guide 45

45 and caused to fall down upon the conveyer in the position indicated at A in Fig. 2. As the envelop moves forwardly beneath the stamp moistening and applying mechanism the lug 19 is engaged with the angular portion 45 of the push rod causing a forward movement of the latter and the consequent operation of the lever 39 and the pawl 40 co-acting with the teeth of the ratchet wheel 41 produces a rotary movement of the shaft 29 carrying the stamp strip supporting roller 28 causing a portion of said strip to 55

unwind from the roller 28 and to be fed between the cutting rollers 29^a and 30^a. Contact of the back of the stamp strip with the roller 29^a causes a quantity of liquid to be deposited thereon due to the perforations 34 in the roller and as the synchronous movement of the rollers 29^a and 30^a is continued the cutting edge 37 is moved across 60 the edge 36 of the roller 29^a producing a

shearing action which severs a section of the stamping strip from the body of the strip and causes the adhesive portion of said stamp to be applied and affixed to the face of the envelop. As the push rod 44 moves forward with the lug it is gradually elevated due to the inclination of the slot 46 and when released is automatically returned to initial position by the influence of the spring 47. The envelop finally passing out of the machine beneath the presser roller 26 is compressed in such manner as to cause the flap 16 to be securely sealed upon the back of the envelop and also to cause the stamp to be pressed upon the front thereof.

What I claim is:

1. In an envelop sealing and stamping machine, a frame structure, a conveyer arranged therein, envelop engaging means carried by the conveyer, a stamp strip supporting roller, means engageable and operable by the engaging means of the conveyer to actuate the roller, a pair of cutting rollers adapted to receive and sever the stamp strip into sections of predetermined length, and means for applying pressure to the envelop to cause adhesion of the stamp thereto.

2. In an envelop sealing and stamping machine, a frame structure, a conveyer arranged therein, envelop engaging means carried by the conveyer, a stamp strip supporting roller journaled in the frame structure, means operable by the engaging means of the conveyer to actuate the roller, companion cutting rollers arranged in the frame structure adjacent the supporting roller, cutting edges carried by the cutting rollers for severing a stamp strip passing therebetween, and means for affixing severed stamps to envelops.

3. In an envelop sealing and stamping machine, a frame structure, a conveyer arranged therein, envelop engaging means carried by the conveyer, a stamp strip supporting roller, means operable by the engaging means of the conveyer to actuate the roller, companion cutting rollers, cutting edges carried by the rollers, adapted to sever a stamp strip into sections during rotation thereof, means for affixing stamp strip sections to envelops and means for connecting the cutting rollers with the supporting rollers whereby movement of said supporting roller is transmitted to the cutting rollers.

4. In an envelop sealing and stamping machine, a frame structure, a conveyer arranged therein, envelop engaging means carried by said conveyer, a stamp strip supporting roller arranged in the frame structure above the conveyer, cutting rollers mounted in the frame structure adjacent the supporting roller and operated thereby, moisture applying means carried by one of said cutting rollers and the other cutting roller being arranged adjacent the conveyer where-

by to affix the cut portion of the stamp strip to an envelop.

5. In an envelop sealing and stamping machine, a frame structure, a conveyer arranged therein, said frame structure having an envelop receiving chamber, envelop engaging means carried by the conveyer, flap moistening means arranged in the frame structure, a guide arranged in the frame structure for engaging and folding the body of the envelop against the flap thereof, a stamp strip supporting roller journaled in

the frame structure, means engageable by the engaging means of the conveyer to intermittently actuate the supporting roller, and 15 stamp strip severing and moistening means actuated by the supporting roller, the other of the companion rollers being arranged adjacent the conveyer whereby to affix the cut portion of the stamp strip to an envelop. 20

In testimony whereof I affix my signature hereto.

STEPHEN J. CIRBUS
